THOMAS MIDGLEY, OF SPRINGFIELD, MASSACHUSETTS, ASSIGNOR TO THE FISK RUBBER COMPANY, OF CHICOPEE FALLS, MASSACHUSETTS, A CORPORATION OF MASSACHUSETTS.

COMBINED MOLD AND FLUID-BAG.

1,321,229.

Specification of Letters Patent.

Patented Nov. 11, 1919.

Application filed January 29, 1919. Serial No. 273,847.

To all whom it may concern:

Be it known that I, THOMAS MIDGLEY, a citizen of the United States of America, residing at Springfield, in the county of 5 Hampden and State of Massachusetts, have invented certain new and useful Improvements in Combined Molds and Fluid-Bags, of which the following is a specification.

My invention relates to the art of vulcanizing casings for pneumatic rubber tires and, more particularly to a combined mold and fluid bag.

It is the common practice to make the fluid bags, used in the cavities of tire casings 15 to press the casings against the molds during vulcanization, as closed annular tubes roughly like inner tubes. But this is not wholly desirable, since it is necessary in putting a closed bag into the casing, to fold, 20 buckle, or otherwise abuse it, which much shortens the life of the bag. The bag of the present invention is open along its inner periphery, whereby the difficulty above referred to is obviated and the bag is long 25 wearing.

When a casing is placed in the mold it is highly desirable that its bases shall be so tightly placed therein as to be highly compressed and compacted. The arrangement 30 of the present invention has means for causing this compression, this provision being closely related to, and coöperating with, the open bag in such a way that the open bag is rendered fluid tight and the bases are compressed by the same operation.

One object of my invention is to provide conveniently operable devices for the compression of the bases of the tire casings.

Another object is to provide an open fluid 40 bag and coöperating devices, so combined that when the mold is being closed the open fluid bag is closed and the bases of the casings are compressed.

To these ends, and also to improve generally upon devices of the character indicated my invention consists in the following matters hereinafter described and claimed.

Without restricting my invention thereto I show and describe it by reference to the 50 devices illustrated in the accompanying drawings; and in these drawings:

Figure 1 is a radial cross section of an annular tire mold of usual construction, but provided with devices in accordance with my invention, a casing being shown in place

in the mold, with the fluid bag received in the casing but not wholly inflated to expand it into full pressing relation to the casing; and

Fig. 2 is a side elevation of the expanding 60 ring and its packing ring.

The illustrated bag 1 is in the character of an endless, annular, flexible tube of fabric and cured rubber with its inner periphery open throughout its length. It is designed to be placed in the casing and expanded to press the casing against the mold M, it being, of course, no part of the casing, but functioning as the usual fluid bag.

The edges of the bag 1 are extended sufficiently to provide for their being folded back beneath the bottoms of the bases B, B, of the casing C, as indicated at 2, 2.

It will be seen that the flexible open character of the bag adapts it for insertion in 75 the casing readily and without crimping, wrinkling, buckling or the like, and hence gives the bag long life. Preferably, and as shown, I prefer to make the bag slightly smaller, before inflation sufficient to stretch 80 it, than the building size of the casing, to additionally guard against buckling.

An expansible ring, as the steel band 3, split (and preferably scarfed) at 4 to permit expansion, is provided for combination 85 with the bag 1. It is adapted to lie in the mold beneath the bases of the tire and bridging the open inner periphery of the bag, to close the bag. A packing element, as the endless sheet of flexible, yielding, and somewhat stretchable, cured rubber 5, serving as a facing for the band 3, is provided. Its function is to act as a packing between the band 3 and the folded back edges of the bag. Also the sheet serves to smoothly span 90 and seal the split 4 of the band.

The mold is provided with a pair of cones 7, 7 which wedge into the circle of the band 3 as the mold is being closed, thereby to expand the band and compress the 100 bases B, B. As here illustrated these cones are provided by expander members or rings 6, 6, fitted to the mold and beveled throughout their peripheries.

This expansion of the band 3 serves two 105 functions. It brings the band 3, the packing sheet 5, and the folded back edges 2, 2, into fluid tight and packed relation; and it compresses the bases B, B of the casing, with pressure exerted directly radially out- 110

ward on the bases in the ideal manner. And it will be noted that these two functions are performed simultaneously.

It will be seen that the arrangement provides that the folded back edges of the bag are grasped and held between two comparatively yielding elements, the sheet 5 and the tire base. Thus, the bag is not subjected to harsh treatment, such as would 10 be inflicted if the edges were clamped between, say, cast iron parts of the mold. Hence the structure has practically no tendency to wear the bag.

When the parts are in place, the bag is 15 inflated as is the usual bag, say by a valve 8 carried by the band 3, the arrangement being fluid tight, and expanded to press the casing to mold M.

It will be seen that I have provided an 20 arrangement of the character indicated, which utilizes an open fluid bag; has substantially no tendency to wear the edges of the bag; provides for the fluid tight closing of the bag; provides for the compression 25 of the bases of the casing; provides for the simultaneous performance of these two last named operations; and which, withal, is simple and comparatively inexpensive to manufacture.

30 What I claim is:—

1. In a device of the character indicated, in combination, a pair of annular mold halves presenting each a cavity, the two adapted to receive a tire casing having a 35 pair of bases, a fluid bag to be received in said casing and open along its inner periphery and having its edges adapted to lie each beneath the adjacent base of the casing, an expansible ring to lie in said mold beneath 40 the bases of the casing and beneath said turned-back edges, and bridging the open inner periphery of said bag, a packing element to lie between said ring and said edges, and an expander-cone carried by each mold 45 half in position to be inserted in said ring to expand the same upon closing of said mold; substantially as described.

2. In a device of the character indicated, in combination, a pair of mold-halves presenting a cavity adapted to receive a tire 50 casing having a pair of bases, a fluid bag to be received in said casing and open along

its inner periphery and having its edges adapted to lie each beneath the adjacent base of the casing, and means operable upon the approach of said mold-halves to force said edges into fluid tight relation with the bases of the casing; substantially as described.

3. In a device of the character indicated, 60 in combination, a pair of mold-halves presenting a cavity adapted to receive a tire casing having a pair of bases and means operatively related to said mold-halves to radially compress said bases, there being an 65 operative connection between said means and said mold-halves for operating said means by said mold-halves by and during the approach of said mold-halves, to radially compress the bases of said casing; substantially as described.

4. In a device of the character indicated, in combination, a pair of mold-halves presenting a cavity adapted to receive a tire casing having a pair of bases, a fluid bag 75 to be received in said casing and open along its inner periphery and having its edges adapted to lie each beneath the adjacent base of the casing, compressing means to lie in said mold beneath the bases of the casing, 80 and beneath said edges and bridging the open inner periphery of said bag, and means for operating said compressing means to compress the bases of the casing and grasp said edges upon the closing of said mold; 85 substantially as described.

5. In a device of the character indicated, in combination, a fluid bag for insertion in a tire casing and inflation therein to press upon said casing, said bag having an opening therealong to permit its easy insertion in the casing, and having portions along the edges of said opening and extending away from said opening in wing-form, and in a direction substantially crosswise of the 95 opening, to thereby adapt them to lie beneath the bases of the casing and a device of a width adapting it to lie across said opening and extend to each side thereof in a direction substantially crosswise of the 10 opening and in packed relation to said portions, thereby to close said bag; substantially as described.

THOMAS MIDGLEY.
